UNITED STATES PATENT OFFICE.

HENRY PETERSEN, OF MOUNT AUBURN, IOWA.

DRAFT-EQUALIZER.

1,099,203.

Specification of Letters Patent.

Patented June 9, 1914.

Application filed December 16, 1913. Serial No. 807,075.

To all whom it may concern:

Be it known that I, HENRY PETERSEN, a citizen of the United States of America, and resident of Mount Auburn, in the county of 5 Benton and State of Iowa, have invented certain new and useful Improvements in Draft-Equalizers, of which the following is a specification.

This invention relates to certain new and 10 useful improvements in draft equalizers or eveners of that class in which the usual horizontal doubletree pivoted upon the tongue is dispensed with, and it has for its 15 objects among others to provide a simple and improved form of draft equalizer or evener which, while designed principally for use on a cultivator or plow, is not necessarily restricted to use upon such class of implements, being capable of use in any and all 20 positions and upon any and all classes of draft vehicles where such devices are desirable.

It has for a further object to provide a 25 draft equalizer of this general character embodying oscillating bearings which are independent of each other and the construction being such as to prevent buckling of the equalizer under the cultivator or other implement from strain.

30 Other objects and advantages of the invention will hereinafter appear and the novel features thereof will be particularly pointed out in the appended claims.

The invention is capable of embodiment in 35 a variety of forms all embracing the same generic feature, namely the independent oscillatory bearings, a few examples of which are illustrated in the accompanying drawings, in which—

40 Figure 1 is a side elevation of a draft equalizer constructed in accordance with my present invention and shown applied to a cultivator. Fig. 2 is a top plan thereof. Fig. 3 is a perspective detail of one-half of 45 the equalizer with a portion broken away. Fig. 4 is a perspective view showing a modified form of equalizer. Fig. 5 is a cross section on the line 5—5 of Fig. 4 looking in the direction of the arrows. Fig. 6 is a perspective view of still another form of the 50 invention. Fig. 7 is a plan view thereof.

Like numerals of reference indicate like parts throughout the several views.

Referring to the drawings, 1 designates

the tongue which, as shown in Fig. 1, may 55 be that of a cultivator of any well known form, of which 2 is the gang frame, or it might be a plow beam or other portion of a different sort of draft vehicle.

Referring first to the construction shown 60 in Figs. 1 and 2, 3 are horizontal members secured to the under side of the rear end of the tongue in any suitable manner, as by an ordinary clip, and these may be tubular or solid, as may be preferred. They serve 65 as supports or bearings for the oscillating members of the evener. In the form shown in Figs. 1, 2 and 3 these bearings 4 are of tubular form and are sleeved upon these horizontal projections 3, 3, so as to oscillate 70 freely thereupon. Rigid with and depending from, and integral with if desired, each member 4 is the member 5, the lower end of which has the horizontal extension 6 provided with a plurality of openings 7. On 75 each member 5 are the bearings 8, properly spaced and in each pair of which the vertical rock shaft 9 is mounted to freely turn. The lower end of each rock shaft 9 is extended substantially horizontally, as seen at 80 10, and provided with an opening 11 for the attachment of a swingletree 12; the upper ends of the rock shafts 9 have the horizontal extensions 13 which, as seen in Fig. 85 3, are disposed substantially at right angles to the horizontal portions 10, and to the outer ends of these horizontal extensions 13 are pivotally connected, as at 14, in any suitable manner the evener bar 15. The extensions 6 of the vertical members 5 are connected by chains 16 with the lower forward 90 ends of the gang frame 2, as seen clearly in Fig. 1. The operation will be apparent and, as seen in Fig. 1, the vertical members 5 are normally extended forward of a perpendicular and the gang frame is in the position shown in full lines. When the lever of the cultivator is operated to throw the gang frame up, the vertical members 5 are thrown 95 rearward into the position shown in dotted lines, the chains 16 permitting the gang frame to assume the position indicated in dotted lines.

Another form of the invention is illustrated in Figs. 4 and 5. In this form the 105 tongue 1 is provided with the tubular extensions 3 near the rear end and the vertical rock shafts 17 for the lateral members

18 at their upper ends which are received within said tubular extensions, thus forming independent oscillatory bearings, the parts simply being a reversal of what is illustrated in Figs. 1, 2 and 3, the operation and result being, however, the same. These rock shafts have sleeved thereon the tubular vertical members 19, the upper ends of which have the horizontal extensions 20, the free ends of which are pivotally connected, as at 21, with the evener bar 22. The tubular members 19 are held against vertical movement upon the rock shafts 17 by the sleeves or collars 23 provided with the set screws 24, or the like 24, permitting of their removal when desired. These vertical tubular members 19 are provided with the longitudinal ribs 25 which are received in grooves 26 in the collars 27 embracing said vertical members 19 and provided with the lateral members 28 having at their outer ends openings 29 for the attachment of swingletrees. The lower ends of the members 17 are provided with the lateral portions 30 having openings 31 for the connection of chains or the like by which they are attached to the lower forward portion of the gang frame as are the members 6 in the form shown in Fig. 1. Set screws 32 may be provided, if desired, for holding the collars 27 at the desired height upon the tubular members 19.

In Figs. 6 and 7 I have shown still another form of embodiment of the invention, in which the tubular members 3, 3 are present as before and upon the same are sleeved the tubular bearings 33 adapted to have independent oscillatory movement the same as in the form shown in Figs. 1 to 3 and in Figs. 4 and 5. Each tubular bearing 33 has a rigid depending arm 34 with a lateral extension 35 at the lower end having openings 36 for the attachment of a chain to connect the same with the forward front portion of the gang frame. Pivotally mounted upon the under side of the tongue upon a suitable pivot 37 is an evener bar 38. 39 are links connected at their forward ends pivotally with the opposite ends of the evener bar 38 and their other ends pivotally connected, as at 40, with the upper end of the substantially vertical members 41 which are attached at about two-thirds of the distance from their lower ends, as at 42, to the horizontal arms or bearings 43 attached to the members 34 and 41, as seen clearly at the left of Fig. 6. The mode of operation is substantially the same in all of the forms hereinbefore described. It is to be noted that the lateral extensions 6, 30 and 35 are provided with a plurality of openings so that the chains may be attached nearer to or farther from the horses as occasion may require, to prevent crowding in or out of the gangs.

65 The supports of the oscillatory bearings

may be mounted on the frame or tongue; the depending members serve as the pivotal seat for the draft strain equalizer or evener, and they also serve to divide the draft strain, partly on the main frame and partly 70 on the cultivator gangs, to hold the earth engaging members down steady against their work. The oscillatory bearings of the upper ends of the depending members serve to keep the members from twisting around so the lateral extensions or feet are rigidly held against their work. The crowding in or out of the gangs on the operator is prevented by the adjustable connection between the lower ends of the depending members 75 and the gang frame. It is evident that the adjustment may be provided for at either the extensions or at the gang frame, the result being the same.

A draft equalizer constructed in accordance with the foregoing description is simple, of few parts, most efficient and reliable in operation and while the structural embodiments of the same as hereinbefore disclosed are what I at the present time consider preferable, it is evident that the same is subject to changes, variations and modifications in details, proportions of parts, etc. without departing from the spirit of the invention or sacrificing any of its advantages. 80 I, therefore, do not desire to limit myself to the exact construction, arrangement of parts and details hereinbefore disclosed, but reserve the right to make such changes, variations and modifications as come properly 95 within the scope of the protection prayed.

What is claimed as new is:—

1. In a draft equalizer, depending members having independent oscillatory horizontal bearings and vertical rockable members movable therewith, and means for attachment to draft appliances and a portion of a vehicle. 105
2. In a draft equalizer, horizontal independent oscillatory members, depending members movable therewith, rockable member movable with said depending members, an evener bar and pivotal connections between the same and said rockable members. 110
3. In a draft equalizer, members having independent oscillatory horizontal bearings, rockable draft attaching members carried thereby, and an evener bar pivotally connected with said rockable members. 115
4. In a draft equalizer, depending members having independent oscillatory horizontal bearings, members rockably mounted thereon and movable therewith and having means for attachment to draft appliances, and an evener bar having pivotal connection 120 with said members.
5. In a draft equalizer, depending members having independent oscillatory horizontal bearings, rockable draft attaching members pivotally mounted thereon and 125

movable therewith, and an evener bar pivotally connected with said draft attaching members.

6. In a draft equalizer, the combination 5 with a tongue having horizontal tubular members thereon, depending members mounted for independent oscillatory movement with relation to said tubular members, draft attaching members rockably mounted 10 on said depending members, and an evener bar pivotally connected with said draft attaching members.

7. In a draft equalizer, the combination 15 with a tongue having horizontal tubular members thereon, depending members mounted for independent oscillatory movement with relation to said tubular members, draft attaching members mounted on 20 said depending members, and an evener bar pivotally connected with said draft attaching members, said draft attaching members being rotatably mounted.

8. In a draft equalizer, horizontal members adapted to have independent oscillatory bearings upon the tongue and depending members having means for attachment 25 to a frame, tubular members mounted upon said depending members, substantially horizontal draft attaching members carried by

said tubular members, and an evener bar 30 pivotally connected with said tubular members.

9. In a draft equalizer, depending members having independent oscillatory horizontal bearings and provided at their lower 35 ends with means for varying the direction of the draft strain to prevent in and out crowding of the gangs, draft attaching members movable with said depending members, an evener bar and pivotal connections 40 between said draft attaching members and the evener bar.

10. In a draft equalizer, depending members having supports for independent oscillatory movement, and means for varying 45 the direction of the draft strain to prevent in and out crowding of the gangs and to hold the earth-engaging members down to their work, said depending members serving as means for applying a part of the 50 draft strain to the main frame and a part to the gang frame.

Signed by me at Washington, D. C., this 16th day of December, 1913.

HENRY PETERSEN.
